CLAIM

The ornamental design for a portable fluid container, as shown and described.

DESCRIPTION

FIG. 1 is an isometric projection of a portable fluid container showing my new design;

FIG. 2 is a front elevational view thereof;

FIG. 3 is a top plan view thereof;

FIG. 4 is a bottom plan view thereof;

FIG. 5 is a lower front exploded isometric projection showing the cap removed from the container;

FIG. 6 is an upper exploded isometric projection showing the cap removed; and,

FIG. 7 is an exploded side elevation view showing the cap removed.
